LUMINESCENT WARNING DEVICE

Filed June 17, 1942.

UNITED STATES PATENT OFFICE

2,342,005

LUMINESCENT WARNING DEVICE

George Mittag, New York, N. Y.

Application June 17, 1942, Serial No. 447,384

5 Claims. (CL 250—71)

My invention relates to an improved luminescent device adapted to be worn by pedestrians and other persons during air raid blackouts, and which will provide a sufficiently luminous visual indication of the presence of the wearers to prevent accidental collision with other persons during such periods, but which will not glow or reflect light to an extent such that it will give an indication of their presence to enemy aircraft which may be overhead at the time.

During blackout periods there is grave danger of injury or death to pedestrians, civilian defense personnel, and others on the streets or in buildings, by reason of accidental collisions, and it has been the experience in certain instances that during air raids more people were injured and killed due to collisions, either with pedestrians or vehicles, than by the bombs. At the same time, it is highly important that no light, either direct or reflected, be present which will guide, or give an indication to, enemy bombers or other hostile aircraft in the vicinity.

Luminous and reflecting devices have heretofore been proposed for this purpose, but these devices have not been entirely satisfactory for various reasons, among which are that the effective luminous or reflecting areas thereof were insufficient or not devised to give the desired warning or indication of the presence of the wearer of the device from different approach angles; the special or complicated nature of the devices has made them difficult or inconvenient to keep or carry during periods when they were not required to be worn; they were difficult to put on quickly and properly during a blackout; they often interfered with the clothing or movements of the wearers, and usually were required to be of different sizes corresponding to the sizes of the wearers.

Among the objects of the invention are to obviate the foregoing disadvantages of the prior devices; to provide a more suitable warning device which has comparatively large luminescent surfaces so that the presence of the wearer, regardless of his size, will readily be discerned at a sufficient distance to avoid collision during total blackout periods; the device makes the presence of the wearer noticeable at all angles of approach, either from the front or rear, by another person in the immediate vicinity; it need be made in but one size which can be worn by men, women and children of all sizes and ages; it is comfortable and convenient to carry or wear; it can be put on quickly and easily even in the dark and is fool-proof in the manner in which it may be

put on or worn; it does not shed light or glow in a manner to make the wearer discernable by enemy aircraft; it is simple in construction and adapted to quantity production methods and thus 5 may be furnished or sold at a low cost; it is light in weight and may be worn with any kind of clothing and without interfering with the movements of the wearer; and the luminescent substance will not crack or peel off, and thereby the 10 device will retain its efficiency and have a long life.

Other objects and advantages will be apparent from the following description, taken in connection with the accompanying drawing, in which:

15 Fig. 1 is a front view of a pedestrian wearing a device in accordance with the invention;

Fig. 2 is a rear view of the wearer and the device of Fig. 1;

Fig. 3 is a plan view of the device in an extended position;

20 Fig. 4 shows certain details of the inner construction of one of the luminescent pads of the device;

Fig. 5 is a fragmentary sectional view, taken 25 along the line 5—5 of Fig. 3; and

Fig. 6 is a detail of one method of construction of the edge portion of the pad.

Referring to Fig. 1 of the drawing, the invention is shown as comprising a pad of sheet 10 30 of flexible material, preferably reinforced cloth, having the exposed outer surface 14 thereof impregnated or coated with a luminescent substance, for example, a paint which is commercially known as phosphorescent paint, and which exhibits luminescence in the dark. As shown, the pad may be made sufficiently large in area so that it substantially covers the chest of the wearer, or that portion of the body from just below the neck or shoulders down to and including the 35 waist. Fig. 2 shows a similar pad 11 having a luminescent surface 15 which covers a substantial portion of the back of the wearer.

In the embodiment illustrated, the pads 10 and 11 are held in position on the chest and back of the wearer by means of flexible straps 12 which pass over and are supported by the shoulders, the ends of the straps being secured in any suitable manner to the upper edges of the pads 10 and 11. The size or area of the pads obviously may 40 be varied within considerable limits, although pads having a longitudinal dimension of eighteen inches and a transverse dimension of eleven inches have been found to be especially suitable, the length of the straps 12 being approximately eleven inches between the pads. In view of the 45

comparatively large luminescent surfaces of the pads, and the fact that they may be worn both on the chest and back, the presence of the wearer regardless of his size will readily be discernible at a sufficient distance to avoid collision during total blackout periods, and moreover the pads make the presence of the wearer noticeable at practically all angles of approach, either from the front or rear, by another person in the immediate vicinity. With the supporting strap arrangement shown, the pads are comfortable and convenient to wear, and the device can quickly be put on over the head of the wearer, even in the dark. Moreover, the device may be worn with any kind of clothing and without interfering with the movements of the wearer, so that the device may be worn over a shirt or blouse, or over a top-coat, overcoat, raincoat, or other article of clothing as the case may be. Preferably, each pad 10 and 11 has a luminescent surface on each side thereof, that is, the underside of the pad as viewed in the figures is luminescent to the same extent as the outer side, and the pads are therefore reversible both with respect to the outer and undersides thereof, and with respect to the front and rear positions of the pads when worn, and thus the device is foolproof in the manner in which it may be put on or worn.

Figures 3 to 6 show various details of the pads, the pads of the device being shown in extended position in Fig. 3.

Figs. 4 to 6 show details of the construction of one of the pads, which preferably is composed of two identical sheets, each of which comprises a woven cloth base, indicated at 17, to which the phosphorescent paint 14 or 15 is applied to the obverse or exposed side thereof, and each of the cloth sheets 17 has a glazed or non-absorbent surface coating 18 on the reverse or inner side thereof. The advantage of having each sheet glazed with a non-absorbent surface 18 is that it prevents the phosphorescent paint from soaking into the sheet 17 to an extent such as to reduce the luminescent effect of the surface 14 or 15, the glazed surface 18 causing the luminous paint or substance to be retained in the woven portion 17 or near the outer exposed surface thereof so as to be most effective in producing the luminescent glow.

Ordinary table oilcloth or thin linoleum provides a good base for each of the two sheets comprising the pad, since such material comprises a woven layer readily adapted to retain the phosphorescent paint, the surface 18 of hardened linseed oil and filler limiting the absorption of the luminescent paint by the woven cloth so that it is retained at or near the exposed surface of the material. Table oilcloth or thin linoleum thus treated also provides a pad which is flexible, and which can be rolled up so that it may conveniently be carried at times when the device is not required to be worn. Moreover, the relatively open fibrous structure of the cloth base 17 prevents the luminescent paint or substance from cracking or peeling off, and therefore the device will retain its efficiency and have a long life. The two identical sheets of the pad of Fig. 4 are turned back to back and stitched around the edges, as indicated at 20, the straps 12 being stitched between these layers, as indicated at 21 in Fig. 4. The device above described also is waterproof and will exhibit the desired degree of luminescence in wet or damp weather as well as in dry weather. The coating of luminescent paint preferably is made

quite thin, and may be applied by a brush, spraying, or other method generally in the manner of application of any paint or stain.

Phosphorescent paint, after being activated by a short period of exposure to a source of artificial or natural light, will glow sufficiently in the dark for a long period of time, for example, eight hours or longer. The pad need only be left lying in a room or other place in 10 a position such that either natural or artificial light is admitted thereto, and upon the occurrence of a blackout is instantly available for use.

The device may be made very inexpensively and by mass production methods, and thus may be furnished or sold at low cost. Also, it is not necessary to make a variety of different sizes of such a device, since the device shown will be found suitable for men, women and children of different sizes and ages.

While the device may be made to exhibit the desired luminescent properties by means of a phosphorescent paint, it will be obvious that other kinds of luminous paints may also be employed. For example, luminous paints composed of zinc sulphide or calcium sulphide, with or without an activating radioactive substance such as radium bromide, may be used; also a paint composed of zinc beryllium silicate with an activating substance may be used. The device exhibits a very noticeable glow in the dark, but does not reflect light to an appreciable extent and for this reason is not objectionable during blackout periods.

It will be understood that, if desired, only one 35 of the pads may be employed, although preferably and to insure greater safety both front and back pads are worn. In the case where only one pad is employed, the straps 12 or other suitable means may be so constructed as to be supported 40 from the neck or other portion of the wearer or his clothes. The device is especially adapted for use during blackout periods, but is also well adapted as a suitable warning device to be worn in the dark by pedestrians, bicyclists, or other 45 persons in general, and substantially reduces or minimizes the hazard of injury to such persons by collision with cars or vehicles on the road on which they may be traveling.

Various other modifications, forms and uses of 50 the device will readily suggest themselves to those versed in the art, without departing from the spirit of the present invention, and I do not desire to be limited except as indicated by the scope of the appended claims.

55 I claim:

1. A luminescent warning device adapted to be worn by a person and to exhibit sufficient luminescence to give a visual warning of the presence of the wearer in the dark, said device comprising 60 a pad having an outer exposed surface of sufficient area to cover substantially the chest of the wearer from just below the shoulders to and including the waist, said exposed portion of the pad comprising a flexible fibrous sheet with the outer surface thereof forming a relatively open fibrous structure, said outer surface having a thin coating of a luminescent paint, and means for securing said pad in operative position on the chest of the wearer.

70 2. A luminescent warning device adapted to be worn by a person and to exhibit sufficient luminescence to give a visual warning of the presence of the wearer in the dark, said device comprising a pad having an outer exposed surface of sufficient area to cover substantially the chest of the

wearer from just below the shoulders to and including the waist, said exposed portion of the pad being composed of a flexible fibrous sheet with the outer surface thereof forming a relatively open fibrous structure, said outer surface having been impregnated with a luminescent paint, the inner surface of the sheet having thereon a coating of a non-absorbent material to prevent undesired absorption of said paint, and flexible strap structure for engaging the body of the wearer to secure said pad in operative position.

3. A luminescent warning device adapted to be worn by a person and to exhibit luminescence to give a visual warning of the presence of the wearer in the dark, said device comprising two pads having outer exposed surface portions sufficient in area to cover substantially the chest and back, respectively, of the wearer, said exposed surface portions each comprising a flexible fibrous sheet with the outer surface thereof forming a relatively open fibrous structure, said outer surface having a thin coating of a luminescent paint, and flexible straps securing said pads together and spaced to receive the head and neck of the wearer between the straps and to rest on his shoulders for securing said pads in operative position.

4. A reversible luminescent warning device adapted to be worn by a person and to exhibit

sufficient luminescence to give a visual warning of the presence of the wearer in the dark, said device comprising a pad composed of two flexible fibrous sheets secured together in superposed position, each exposed surface of the pad being of sufficient area to cover substantially the upper body portion of the wearer, each said sheet having the fibrous outer surface thereof impregnated with a luminescent paint and each having the inner surface thereof impregnated with a non-absorbent material to prevent undesired absorption of said paint, and means for securing said pad in operative position on the body of the wearer.

5. A reversible luminescent warning device adapted to be worn by a person and to exhibit sufficient luminescence to give a visual warning of the presence of the wearer in the dark, said device comprising a pad having two woven cloth sheets secured together in superposed position so that the opposed outer faces of the pad each comprises a woven structure, said outer faces being impregnated with a luminescent paint, the inner faces of said sheets each having a glazed surface coating to prevent undesired absorption of said paint, and means for securing said pad in operative position on the body of the wearer.

GEORGE MITTAG.
